UNITED STATES PATENT OFFICE

135,926

DESIGN FOR A COMBINATION COMB, BRUSH, AND MIRROR

Dawson W. Spurgeon, Salem, Ind.

Application May 5, 1943, Serial No. 110,129

Term of patent 7 years

To all whom it may concern:

Be it known that I, Dawson W. Spurgeon, a citizen of the United States and resident of Salem, in the county of Washington, in the State of Indiana, have invented a new, original, and ornamental Design for a Combination Comb, Brush, and Mirror, of which the following is a specification, reference being had to the accompanying drawing, forming a part thereof.

Fig. 1 is a front elevational view, Fig. 2 is a side elevational view, and Fig. 3 is a top plan view, of a combination comb, brush, and mirror, showing my design.

I claim:

The ornamental design for a combination comb, brush, and mirror, as shown.

DAWSON W. SPURGEON.
